UNITED STATES PATENT OFFICE.

DAVIS R. BOOGHER, OF ST. LOUIS, MISSOURI.

INCrustation PREVENTIVE.

SPECIFICATION forming part of Letters Patent No. 406,698, dated July 9, 1889.

Application filed December 15, 1888. Serial No. 293,668. (No specimens.)

To all whom it may concern:

Be it known that I, DAVIS R. BOOGHER, of the city of St. Louis, in the State of Missouri, have invented a certain new and useful Im-
5 provement in Boiler Compounds, of which the following is a full, clear, and exact de-
scription.

My invention relates to an improved com-
pound for the prevention and removal of scale
10 in boilers; and my invention consists in a
compound composed of the following parts,
in or about the proportions named, viz: Ex-
tract of hemlock, three hundred and eighty
pounds; gambia, one hundred pounds; sumac,
15 one hundred pounds; wormwood, fifty pounds,
and salts of tartar, fifty pounds.

I do not confine myself to the above-named proportions of these parts, as they may be varied; but the proportions given form a com-
pound which is effective in performing the 20 functions for which it is intended.

I claim as my invention—

A boiler compound consisting of extract of hemlock, gambia, sumac, wormwood, and salts of tartar, mixed together in about the pro- 25 portions named.

DAVIS R. BOOGHER.

In presence of—
GEO. H. KNIGHT,
EDW. S. KNIGHT.
